(57) **CLAIM**

We claim the ornamental design for an outdoor studio flash, as shown and described.

DESCRIPTION

FIG. 1 is a Perspective view of an outdoor studio flash showing my new design;

FIG. 2 is a Front view thereof;

FIG. 3 is a Rear view thereof;

FIG. 4 is a Right-side view thereof;

FIG. 5 is a Left-side view thereof;

FIG. 6 is a Top view thereof; and,

FIG. 7 is a Bottom view thereof.

The broken lines immediately adjacent to the shaded areas depict the bounds of the claimed design, while all other broken lines are directed to environment. The broken lines form no part of the claimed design.

The "NEEWER" lettering and icon forming part of the disclosure is a registered trademark of HENZHEN XING YING DA INDUSTRY CO. LTD.

1 Claim, 7 Drawing Sheets
